CLAIM

The ornamental design for a dog harness, as shown and described.

DESCRIPTION

FIG. 1 is a top, front, left perspective view of a dog harness showing my new design, in condition of use on a dog; FIG. 2 is a top, front, left perspective view of the dog harness of FIG. 1;

FIG. 3 is a top, rear, right perspective thereof; FIG. 4 is a front elevational view thereof; FIG. 5 is a rear elevational view thereof; FIG. 6 is a left side elevational view thereof; FIG. 7 is a right side elevational view thereof; FIG. 8 is a top plan view thereof; and, FIG. 9 is a bottom plan view thereof.

In the drawings, the broken lines on the body of the harness depict stitching and form no part of the claimed design. The broken line showing of dimensional elements on the harness (hardware, fasteners, straps) depicts environmental subject matter only and forms no part of the claimed design. In FIG. 1, the broken line showing of a dog depict environmental subject matter only and forms no part of the claimed design.
